FUEL REGULATOR FOR MOTOR TEMPERATURE CONDITIONS

Lester H. Messinger, Jr., Trumbull, Conn., assignor to Messinger Devices, Incorporated, Bridgeport, Conn., a corporation of Connecticut

Application February 17, 1939, Serial No. 256,881

16 Claims. (Cl. 123—119)

This invention relates to new and useful improvements in fuel feeding means for internal combustion engines and has particular relation to means for facilitating the starting and the operation of a cold internal combustion engine.

The objects and advantages of the invention will become apparent from a consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention and the scope of the appended claims.

In the drawings—

Fig. 1 is a view partly in side elevation and partly in section showing an embodiment of the invention as applied to a horizontally operating engine equipped with an up-draft carburetor, the parts being positioned as when the engine is cold and is not operating;

Fig. 2 is an enlarged view partly in section and partly in elevation and showing in detail the relation of the invention to one construction of carburetor, the parts of the device of the invention being positioned as when the engine is idling but cold;

Fig. 3 is a side elevational view of a means employed in practicing the invention;

Fig. 4 is an enlarged sectional view through the head-like portion of the means of Fig. 3 and showing the valve therein completely closed as when the engine equipped with the device of the invention is at an operating temperature; and

Fig. 5 is an end elevational view of the control means of the invention, the view being taken as looking downwardly from the upper end of Fig. 3.

Referring in detail to the drawings at 10 is shown a portion of a horizontally arranged internal combustion engine of an automobile. Explosive mixture is fed to the engine 10 from a carburetor 11 through an intake line or conduit generally designated 12. It is to be understood that the invention is not limited in its application to the type of engine shown and further is not limited to the up-draft type of carburetor later herein described.

Intake line 12 has a main explosive mixture feeding passage 13 therethrough and as shown includes a portion having a jacket 14 thereabout and through which hot exhaust gases from the engine are passed. This construction provides what is well known as a hot spot about a portion of the mixture passage for the purpose of as-

sisting in the vaporizing of the gases passing to the engine. Beyond the jacket 14 a manifold 15 serves to provide a portion of the passage 13 and has arms 16 connected with the engine block.

5 Carburetor 11 is of well known make and includes a liquid fuel chamber 17, an air inlet 18, and a riser portion connected with the lower end of the line or conduit 12 and providing an explosive mixture passage 19. Within the carburetor an opening 20 in a wall 21, together with a tube 22 provides a balancing passage connecting the upper portion of the chamber 17 (above the level of the liquid fuel therein) with the air inlet 18. The capacity of such balancing passage 15 is kept small as by the insertion therein of a restricting device 23.

The carburetor includes upper and lower portions 24 and 25 between the adjoining edges of which is arranged a sealing gasket 26. Gasoline or other liquid fuel is supplied to the carburetor through an inlet 27 and the level of the fuel in the chamber 17 is controlled by a valve 28 in turn controlled by a float 29. Through a metering jet 30 fuel from the chamber 17 is admitted to a passage 31 from which it enters the main discharge jet or nozzle 32 of the carburetor and from the discharge end 33 of which the fuel is taken up by air drawn through the large and small venturis 34 and 35 when the engine throttle valve 36 is open and the engine is operating. Associated with the main discharge jet 32 is the usual high speed bleed jet 37.

Carburetor 11 is provided with the usual tube 38 to the idle discharge opening 39 and with a plug 40 for said discharge, this being the usual construction. A vacuum type accelerator pump, forming part of the carburetor, is generally designated 41 and includes a vacuum piston 42 communicating with the fuel passage 19 through the riser portion thereof above the throttle valve 36, as through a port or passage 43. An accelerator pump piston 44 is connected with the lower end of rod 45 and a coil spring 46 surrounds said rod.

When a high degree of vacuum is created in the passage 19 it is communicated to the piston 42 (through the passage 43) and draws the same upwardly resulting in the pump piston 44 being drawn upwardly to suck gasoline into the pump from the chamber 17 and at the same time compress the spring 46. On the degree of vacuum in the passage 19 being materially reduced the spring 46 acts or expands to cause the pump 41 to discharge through the passage 47 into the main jet 32 at 48.

Owing to the use of an air cleaner (not shown)

together with its connections there is a static suction pressure in the air inlet passage 18 and the purpose of the passage through the tube 22 and the wall 21 is to equalize such suction pressure in said passage 18 and in the fuel chamber 17.

17. Thus the effect of static suction pressure in the fuel feeding or mixing chamber of the carburetor is cancelled out due to the same static suction pressure existing in the chamber 17. Therefore, under normal operating conditions 10 fuel is fed to the engine only due to the velocity pressure in the fuel feeding or mixing chamber of the carburetor.

Heretofore it has been the custom to mount a choke valve in the air inlet 18 whereby on closing of such valve the suction pressure in the mixing or fuel feeding chamber of the carburetor is increased for the purpose of supplying additional fuel to the engine. Thus starting and operation of the engine while cold has been facilitated.

According to the present invention the choke valve is omitted and the top of the fuel chamber is tapped as at 49 for the admission of atmospheric pressure to the upper portion thereof. Connected with the opening 49 by means of fittings 50 is the lower end of a tube 51 having its upper end 52 mounted in a bracket device 53 secured above the carburetor against a side of the jacket 14.

Bracket 53 includes an elongated body 54 having a hollow head-like portion or casing 55 at the lower end thereof. Said bracket is provided with openings 56 for the passage of securing means used in attaching the bracket to the jacket 14 or otherwise as desired. Portion 55 of the bracket includes a hollow internally threaded protuberance 57 communication under certain conditions with the atmosphere as will appear. A fitting 58 serves to connect the upper end 52 of the tube 51 with the protuberance 57 whereby when the latter is in communication with the atmosphere air is admitted to the upper portion of the liquid fuel chamber 17 through the tube 51.

A tube 59 of smaller internal diameter than tube 51 has its lower end portion connected with the liquid fuel chamber 17 below the level of the fuel therein, the connection being made as through an elbow fitting 60. The upper end portion 61 of the tube 59 enters into and is secured in a spider-like member 63 as by a fitting 62. A set screw 64 serves to secure the member 63 in place in the bracket portion.

At its inner end tube portion 61 discharges through a jet 65 into an air stream provided for this purpose as will later appear. An internally threaded extension 66 on the inner end of the bracket portion 55 has connected thereto the upper end of a tube 67 of greater internal diameter than that of the tube 51. Any suitable means, as the elbow fitting 68 may be used for this purpose. The lower end of tube 67 is connected to discharge into the main fuel passage 13 through a port 69 located at the engine side of the throttle valve 36.

Within the bracket portion 55 and the extension 66 thereof is a passage 70 having located therein a slidably mounted valve member 71 provided with a passage or notch 72 adapted to place the interior of the protuberance 57 in communication with the atmosphere through an opening 73 as will appear. Valve member 71 also includes a flat end 74 constituting a valve adapted to engage a seat 75 and close off communication between the passage 70 and the tube 67. In-

termediate its ends the valve member 71 is notched as at 76 whereby to receive the lower end of a bimetallic thermal element 77 the upper end of which is secured to the bracket body as 5 by a nut and bolt means 78.

Valve member 71 is hollow having a passage 79 extending longitudinally thereof and opening through its end portion 80. Toward its other end the member includes the valve portion 74 and a plurality of outlet openings (six such openings being shown) 81 placing the passages 70 and 79 in communication. Portion 74 of the valve member is flat ended to provide a considerable area to be acted on by engine suction at certain times as will appear.

The spider 63 has openings or ports 82 therein adapted to place the passages 70 and 79 in communication with the atmosphere as will later be fully described. Associated with the bimetal thermal element 77 is a second and stiffer bimetallic thermostatic element 83 also secured to the bracket portion by the nut and bolt means 78. Element 83 is held to a limited movement in one direction by a stop screw 84 threaded through the bracket body 54 and passing freely through an opening 85 provided for that purpose in the element 77.

Assuming that the engine is cold the parts of the present fuel regulator will be positioned as in Fig. 1 with the thermal element 77 holding the valve member 71 with its end 80 against the inner end of the spider 63. While the thickness of the walls of the inner end of the valve member is such with relation to the locations of the ports 82 as to close the ports attention is directed to the fact that the engaged portion of the spider is convex. Therefore the valve member has only a line contact with the spider, the contact being about the edge of the passage 79. Thus while air cannot enter the passage 79 from the ports 82 atmospheric pressure is against the end of the valve member. Also the notch 72 in the valve member is located to provide for communication of the atmosphere with the interior of the protuberance 57 and the tube 51 and thence into the upper portion of the float or liquid fuel chamber 17.

The valve member being positioned as indicated its valve portion 74 is spaced from the seat 75 and under conditions of low suction in the engine (that is, during cranking of the engine by the usual self starter), the throttle valve 36 being closed, liquid fuel will be drawn from the carburetor chamber 17 upwardly through the tube 59 to the jet 65. Since there is atmospheric pressure against the end 80 of the valve member the engine suction through the tube 67 is fully effective on the large end 74 during cranking of the engine—the valve member is drawn away from the spider 63 a slight distance providing a restricted opening or passage for the entrance of air through ports 82. Now the engine suction has acted to set up an air stream through the valve member. Jet 65 sprays fuel into this air stream and the mixture of air and fuel is taken promptly into the engine through passages 79 and 70 and the tube 67 entering the passage 13 above the throttle valve. Attention is directed to the fact that the air and fuel are thus brought together and mixed at the point of highest velocity in the auxiliary fuel feeding system, such point being at the restriction or restricted passage part between the valve end 80 and the spider 63.

The first fuel leaving the jet 65 is thus prompt-

ly fed to the engine during cranking thereof to provide a very rich mixture constituting a priming charge for the starting of the engine. As soon as the engine begins to fire the engine suction is increased due to the more rapid action of the pistons therein and this increased suction will act through the tube 67 on the valve member 71 tending to draw the same further toward the valve seat 75.

Since when cranking of the engine is started 10 the ports 82 are closed the vacuum in the passage 79 is nearly the same as that in the passage 13 at the engine side of the throttle valve 36. The suction moves the valve member 71 against the action of the thermal element 77 with the result that air enters through the ports 82 and mixes with and picks up the fuel from the jet, the mixing taking place at the point of highest velocity as above set forth. The described condition is true while the engine is cold and is being cranked and the colder the engine the more the element 15 77 forces the valve member against the spider 63 and the less the same moves away from the spider during cranking and therefore the higher the proportion of fuel in the mixture passing to the engine.

Element 77 functions as a spring to keep the valve member in the position of Fig. 1 but such element becomes less and less of a spring as it becomes heated during operation of the engine. Element 77 is so set or deflected that it is under tension in the position of Fig. 1 and is constantly, while cold, urging the member toward the position of Fig. 1. Actually while element 83 is heavier it is set under more tension but less deflection than the thinner element 77. When the engine begins to fire the increased suction therein being transmitted to the flat end 74 of the valve member the latter is drawn toward closed position but such movement is limited by the thermal element 83 so that the valve member can move only a predetermined distance (as to the position of Fig. 2) toward closed position. Thus irrespective of engine suction a rich idling mixture to the engine is insured, the engine being 45 cold.

As the engine begins to fire the increased engine suction exerted on the valve end 74 results in movement of the valve member to the position of Fig. 2. There it will be noted that the element 77 is against the element 83. It is to be borne in mind that both the elements 77 and 83 are as yet cold and thus the element 83 serves to limit movement of the element with the valve member so as to limit movement of the latter under the suction exerted thereon by the engine. The parts being positioned as in Fig. 2 it will be clear that the inner end 80 of the valve member has moved further from the ports 82 whereby additional air is being admitted to the passage 60 79 and thus to the entrance end of tube 67. Now the engine is idling on a rich mixture.

The air admitted through ports 82 as described mixes with the liquid fuel being sprayed by the jet 65 but it will be understood that when the 65 engine begins to idle more air and less fuel is fed the engine than during the cranking operation. That is a very rich mixture is supplied the engine during cranking and a rich mixture is fed the engine when it begins to idle. With the valve member in the position of Fig. 2 the notch 72 is yet in communication with both the opening 73 and the passage through the protuberance 57 whereby air at atmospheric pressure is present in the upper portion of the fuel chamber 75

17. Air tube 51 is of such size as to supply air in quantity to more than compensate for the air taken through the balancing tube 22 above described.

5 It is to be noted that the explosive mixture of fuel and air fed into the engine both for priming and while idling as above described (through the tube 59 and associated parts) is fed independently of the usual carburetor jets. The tube and its associated parts provide in effect an auxiliary idling jet for the engine while the latter is cold. As the engine warms up, the thermal elements being mounted on the jacket 14 will also be heated and will tend to move toward the left as viewed in Figs. 1, 2 and 4. As the two elements heat up and both move the tendency of the valve member 71 is to bring the portion 74 against the seat 75.

As the elements 77 and 83 gradually heat they 20 have a gradual tendency to move the valve member to position seating the valve 74. The suction of the engine arguments this tendency of the thermal elements and in fact the movement of the valve member due to engine suction keeps 25 the valve in advance of any movement that would be given it by the thermal elements as they heat up. After the valve member reaches the position of Fig. 2 on further softening of the elements 77 and 83 a high engine suction acting on the end 74 of the valve member will cause the same to suddenly close.

This is due to the fact that movement of the mixture about the valve 74, that is between the valve and its seat 75, is restricted and substantially the entire suction through the tube 67 is directed against the large area of the flat end 74 of the valve member. When the engine reaches the desired operating temperature the thermal elements have moved in accordance with 30 their nature and are holding the valve member in the position of Fig. 4 wherein it will be seen that the valve portion 74 is engaged with its seat 75 closing off communication between the passage 79 and the tube 67. Also it will be noted in Fig. 4 that the notch 72 has moved out of communication with the opening 73 and thus the carburetor 45 11 is functioning in a normal manner without the aid of any of the parts comprising the invention.

50 From the foregoing it will be noted that during cranking of the engine while cold a very rich mixture—a mixture depending on engine temperature—is supplied to the engine and that as the engine begins to fire the mixture fed the engine is leaned out but yet the engine is fed a rich mixture while idling cold. During both idling and cranking the richness of the mixture fed the engine depends on the engine temperature since the element 77 is not only a spring 55 but is also a thermostat. In the operations as described above the throttle valve of the engine has been closed. Should the operator open the throttle valve the vacuum on the member 71 is reduced.

Thereupon, the engine being cold, the member 71 under the urging of the element 77 will tend to move back toward the position of Fig. 1 from any position in advance of that position. When this happens a very rich charge of fuel is again fed the engine. Likewise as the engine begins to fire should the suction fail the valve member will function as above. That is, it will move toward the right as viewed in the drawings partly closing the ports 82 whereupon the vacuum will

act to draw liquid fuel in increased amount through the tube 59 to accelerate the engine.

While atmospheric pressure is maintained in the upper portion of the float chamber due to the fact that the tube 51 is supplying air to such chamber faster than it is being exhausted therefrom through the balance tube 22, a differential pressure exists between the fuel passage or mixing chamber and the float chamber with the result that additional fuel will be fed through the tube 59 whenever there is a suction thereon whereby to keep the engine operating at idling speed while cold.

As the valve part 14 approaches the seat 75 the portion of the valve member acted on by the suction becomes more subject to such suction and thus the effect of the suction on the valve member is increased. Therefore under engine suction the valve member will suddenly move from the position of Fig. 2 to that of Fig. 4 when the elements 77 and 83 are soft but have not as yet caused the valve to close. Thus without waiting for the thermal elements to act, when the mixture being fed the engine through the auxiliary means of the invention, leans out below explosive proportions, the valve promptly closes. When the valve member closes the ports 82 are fully open and there being no suction in the passage 79 the fuel in the tube 59 will immediately drain back into the fuel chamber of the carburetor.

Having thus set forth the nature of my invention, what I claim is:

1. In combination, an internal combustion engine, a carburetor for supplying explosive mixture to said engine, a conduit for such mixture between the carburetor and the engine, a throttle valve in said conduit, said carburetor including a liquid fuel chamber, said conduit including a hot spot spaced vertically above said carburetor, a bracket means mounted on said hot spot, said bracket means including a passage, means connecting one end of said passage with the interior of said conduit at the engine side of said throttle valve, a tube having its upper end connected with the other end of said passage and having its lower end connected with the interior of said liquid fuel chamber below the level of the fuel therein, a valve member mounted in said bracket means, said bracket means including a second passage, a tube connecting one end of said second passage with the upper portion of the liquid fuel chamber, said valve member adapted to place the other end of said second passage in communication with the atmosphere and shiftable to and from a position closing both of said passages, and a thermostat mounted on said bracket means and connected to shift said valve member.

2. In combination, an internal combustion engine, a carburetor for supplying explosive mixture to said engine, a conduit for such mixture between the carburetor and the engine, a throttle valve in said conduit, said carburetor including a liquid fuel chamber, a bracket means mounted above said carburetor and located to be effected by the heat of said engine, said bracket means including a passage, means connecting one end of said passage with the interior of said conduit at the engine side of said throttle valve, a tube having its upper end connected with the other end of said passage and having its lower end connected with the interior of said liquid fuel chamber below the level of

the liquid fuel therein, a valve member mounted in said bracket means, said bracket means including a second passage, a tube connecting one end of said second passage with the upper portion of the liquid fuel chamber, said valve member adapted to place the other end of said second passage in communication with the atmosphere and shiftable to and from a position closing both of said passages, a thermostat mounted on said bracket means and connected to shift said valve member, and means admitting air to said first mentioned passage to support combustion of fuel drawn therethrough and to provide for quick drainage of the said passage and the first mentioned tube on closing of said first mentioned passage by the valve member.

3. In a priming device, an intake manifold for an internal combustion engine, a carburetor attached thereto and including a fuel reservoir, a casing connected with the manifold, a valve actuated by the engine suction in the casing for regulating the connection between the intake manifold and the casing, means to supply liquid fuel from the reservoir to the casing, means responsive to the engine temperature for controlling the position of said valve, and said means responsive to engine temperature mechanically operative to hold said valve open and prevent closing thereof by engine suction until after the engine has reached a predetermined operating temperature.

4. In a fuel feeding system for internal combustion engines, an intake pipe having a throttle valve therein, a port in said pipe at the engine side of said throttle valve, means for supplying explosive mixture to said pipe at the side of the throttle valve opposite that at which the engine is located, means for supplying an air stream to said port, a jet to inject a spray of fuel into said air stream, and means to increase the air supply in said stream without changing said jet as the engine suction increases and to close and cut off the supply of both fuel and air to said port when said mixture leans out below explosive proportions.

5. In a fuel feeding system for internal combustion engines, an intake pipe having a throttle valve therein, a port in said pipe at the engine side of said throttle valve, means for supplying explosive mixture to said pipe at the side of said throttle valve opposite that at which the engine is located, means for supplying an air stream to said port, a jet to inject a spray of fuel into said air stream, means to increase the supply of air in said stream without changing said jet as the engine suction increases and to close off the supply of both fuel and air to said port when such mixture leans out below explosive proportions, and thermal means operable to hold said cut off means in closed position on the engine reaching an operating temperature.

6. In a fuel feeding system for internal combustion engines, an intake pipe having a throttle valve therein, a port in said pipe at the engine side of said throttle valve, means for supplying explosive mixture to said pipe at the side of said throttle valve opposite that at which the engine is located, means for supplying an air stream to said port, a jet to inject a spray of fuel into said air stream, and means controlling said air stream to increase the air supply in said stream without changing said jet as the engine suction increases and thereafter decrease the volume of air in said stream on return of low suction in

the engine and to stop said air stream on the engine reaching an operating temperature.

7. In a priming device, an intake manifold for an internal combustion engine, a carburetor attached thereto, a casing, a connection between said casing and the interior of said manifold, a valve in said casing and actuated by the engine suction for regulating the connection between the manifold and the casing, said valve being hollow and having an inlet and an outlet, means for supplying fuel and air to the valve inlet in proportion depending on the position of the valve, said valve outlet adapted to discharge said fuel and air through said connection into the manifold when the valve is open, and a thermal means connected with said valve to draw it open and into positions receiving proportionally richer mixtures as the engine is colder and restraining the valve against closing movement under the influence of engine suction when the engine is cold and operable to hold the valve closed cutting off the supply of mixture therethrough on the engine reaching an operating temperature.

8. In a priming device, an intake manifold for an internal combustion engine, a carburetor attached thereto, a casing, a connection between said casing and the interior of said manifold, a valve in said casing and actuated by the engine suction for regulating the connection between the manifold and the casing, said valve being hollow and having an inlet and an outlet, means for supplying fuel and air to the valve inlet in proportion depending on the position of the valve, said valve outlet adapted to discharge said fuel and air through said connection into the manifold when the valve is open, a thermal means connected with said valve to draw it open and into positions receiving proportionally richer mixtures as the engine is colder and restraining the valve against closing movement under the influence of engine suction when the engine is cold and operable to hold the valve closed cutting off the supply of mixture therethrough on the engine reaching an operating temperature, a valve seat at the valve end of said connection, said valve having an end of large area adapted to be acted on by engine suction whereby to draw the valve toward said seat, and said valve adapted to engage said seat only about the edge of the valve whereby to have said large end area subject to engine suction while the valve is closed.

9. In a priming device, an intake manifold for an internal combustion engine, a carburetor attached thereto, means for initially supplying a very rich priming mixture of fuel and air to the intake manifold at a point at the engine side of the throttle from the carburetor responsive to engine suction, means responsive to engine suction and temperature for cutting off said priming charge from the intake manifold, said means responsive to engine temperature comprising a pair of independent spring-like thermal elements one of which is slight and connected to said valve to be moved thereby when the valve is moved by engine suction and to hold the valve closed when the engine is at an operating temperature, and the other of said elements not connected with the valve and located in the path of movement of the first element to limit initial movement thereof and of the valve.

10. In a priming device, an intake manifold for an internal combustion engine, a carburetor attached thereto, means for initially supplying a rich priming charge of fuel and air to the in-

take manifold at the engine side of the throttle responsive to engine suction and temperature and for cutting off said priming charge from the intake manifold on the engine reaching an operating temperature, and a second means responsive to engine temperature and operative to limit the effectiveness of engine suction on said first means until the engine reaches said operating temperature.

10 11. In combination, an internal combustion engine, a carburetor for supplying explosive mixture to said engine, a conduit for such mixture extending between the carburetor and the engine, a throttle valve in said conduit, said carburetor including a liquid fuel chamber, means for admitting air to the upper portion of said chamber, means providing a passage through which explosive mixture including fuel from said chamber may be drawn into said conduit at the engine side of said throttle valve, a single valve means controlling the opening and closing of both said means, and thermal means operable to close said valve means on the engine reaching an operating temperature.

20 12. In a priming device, an intake manifold for an internal combustion engine, a carburetor attached thereto, a casing, a connection between said casing and the interior of said manifold, a valve in said casing and actuated by the engine suction for regulating the connection between the manifold and the casing, said valve being hollow and having an inlet and an outlet, a fixed pair of ports for supplying fuel and air respectively to the valve inlet in proportion depending on the position of the valve relative to the air port, said valve outlet adapted to discharge said fuel and air through said connection into the manifold when the valve is open, and a thermal means connected with said valve to draw it open and into positions receiving proportionally richer mixtures as the engine is colder and restraining the valve against movement away from said air port toward closing position under the influence of engine suction when the engine is cold and operable to hold the valve closed stopping the supply of mixture therethrough on the engine reaching an operating temperature.

13. In a priming device, an intake manifold for an internal combustion engine, a carburetor attached thereto, a casing, a connection between said casing and the interior of said manifold, a valve in said casing and actuated by the engine suction for regulating the connection between the manifold and the casing, said valve being hollow and having an inlet and an outlet, means for supplying fuel and air to the valve, said valve outlet adapted to discharge said fuel and air through said connection into the manifold when the valve is open, a thermal means for holding the valve closed on the engine reaching an operating temperature, a valve seat at the valve end of said connection, said valve having an end of large area adapted to be acted on by engine suction whereby to draw the valve toward said seat, said valve having its outlet laterally and inwardly of said end whereby the latter is left imperforate, and said valve adapted to engage said seat along the peripheral edge only of said valve end of large area whereby to have the whole surface of said end of large area subject to engine suction while the valve is closed.

70 14. In a priming device, an intake manifold for an internal combustion engine, a carburetor for supplying explosive mixture thereto, means for initially supplying a rich priming charge to

said intake manifold at the engine side of the throttle responsive to engine suction and temperature and for supplying a fast idling charge to the manifold at the engine side of the throttle valve as the engine begins to fire and for stopping said fast idling charge on the engine reaching an operating temperature, and a second means operative to limit the effectiveness of engine suction on said first means until the engine reaches an operating temperature.

15. In a fuel feeding system for an internal combustion engine having an intake pipe provided with a throttle valve, means to supply a mixture of fuel and air to said pipe at the engine side of said throttle valve, said means comprising a tubular valve member, a fuel jet at one end of said valve and in alignment with the opening therethrough, means for admitting air at a side of the fuel jet, said valve movable to and from a position where one end of the valve closes said means to control the volume of air admitted therethrough and thereby the suction pressure on the jet and the richness of the mixtures fed the intake pipe, a thermostat cooperating with

the suction of the engine and controlling the position of the valve relative to said means, and said thermostat operable to move said valve to a position stopping the said feed of mixture on the engine reaching a predetermined temperature.

16. In a fuel feeding system for an internal combustion engine having an intake pipe provided with a throttle valve, means to supply a mixture of fuel and air to said pipe at the engine side of said throttle valve, said means comprising a tubular valve member, a fuel jet at one end of said valve and in alignment with the opening therethrough, means for admitting air at a side of the fuel jet, said valve movable to and from a position where one end of the valve closes said means to control the volume of air admitted therethrough and thereby the suction pressure on the jet and the richness of the mixtures fed the intake pipe, and a thermostat cooperating with the suction of the engine and controlling the position of the valve relative to said means.

LESTER H. MESSINGER, JR.
